INTERNAL COMBUSTION ENGINE

Wilhelm B. Bronander, Montclair, N. J., assignor
to The Safety Car Heating & Lighting Com-
pany, New Haven, Conn., a corporation of New
Jersey

Application October 7, 1931, Serial No. 567,354

41 Claims. (Cl. 123—51)

This invention relates to improvements in internal combustion engines of the opposed piston Diesel type and its object is to provide an engine of simple construction and great efficiency.

More specifically, its object is to provide a novel arrangement for compressing air for scavenging and charging the working cylinder, in which the air is kept out of the crank case, where in former constructions it was subject to contamination from oil and vapors.

These and other objects of the invention will appear in the following specification in which I will describe the invention fully, the novel features of which will be set forth in appended claims.

Referring to the drawings,

Figs. 1 and 2 are sectional elevations at right angles to each other of an engine which is made according to and embodies this invention;

Fig. 3 is a sectional plan view, the section being taken on the line 3—3 of Fig. 2;

Fig. 4 is a sectional plan view, the section being taken on the line 4—4 of Fig. 1; and

Fig. 5 is a sectional elevation on a larger scale of some of the parts shown in Fig. 1.

10 designates the frame of the engine in which is mounted the crank shaft 11. This has one crank connected by a rod 12 with a working piston 13 and two cranks opposed to the first mentioned crank connected by rods 14, 14 with a yoke 15 which supports the other working piston 16. The pistons 13 and 16 are in a cylinder 17 which, as may be seen from Fig. 2, is integral with the frame 10. 18 is its water jacket, 19 the exhaust ports and 20 a fuel inlet port.

21 designates the head of the engine. It is constructed to form an oblong rectangular compression chamber 22 having flat walls parallel with the axis of the cylinder 17 in which the yoke 15 reciprocates and two air storage chambers 23, 23. The chambers 23 are in open communication with the cylinder 17 through aligned ports 24 in the head 21 and the frame 10 and ports 25 in the cylinder. 26 is a part of the frame 10 forming a wall which keeps the entrapped air above it and out of the crank case and the part of the frame 10 and between the crank case and the head 21.

The sides 27 of the yoke 15 which contact with the longer walls of the compression chamber 22 are flat, as may be seen from Figs. 2 and 3, and form a sliding fit therewith. The ends 28 of the yoke may be curved, as shown in Figs. 1 and 5. These form a sliding fit with the shorter walls of the chamber 22 and prevent the yoke from jamming by getting out of alignment.

The piston 16 is preferably affixed to the yoke 15 in the manner shown somewhat in detail in Fig. 5. This shows that the central part of the yoke is constructed with spherical surfaces 30, 31. The upper end of the piston abuts against the lower spherical surface 31. It is internally threaded to receive external threads on the shank of a hollow cap 32 which has a flange 33 abutting against the upper spherical surface 30. Thus both the yoke 15 and the piston 16 are readily aligned with the stationary parts within which they reciprocate.

A check valve 34 seating against the end of the shank of cap 32 may be provided. 35 is a spider for supporting the stem of this check valve and 36 is a spring biasing it to close.

Piston 16 is hollow except at its lower end and is provided with ports 37 which during the upper part of the piston stroke register with the ports 25 in the cylinder wall, as shown in Fig. 1. By referring to Fig. 4 it may be seen that the ports 25 and 37 are cut obliquely through the cylinder 17 and the piston 16 respectively.

40 is a cap on the upper end of the head 21. This forms a chamber 41 in open communication with the surrounding air. It is provided with check valves 42 which permit air to pass freely into the chamber 22 but prevent it from passing upwardly therefrom.

The operation is as follows: When the cranks are in the positions shown in Fig. 1 the pistons 13 and 16 are at the outer ends of the working stroke and the yoke 15 is at the upper end of its stroke in compression chamber 22. Air which has been compressed in a manner which will be described, passes down through the ports 25 into the cylinder 17 with a swirling motion, down through the cylinder and out through the exhaust ports 19. Thus the cylinder is thoroughly scavenged.

When the pistons move towards each other the exhaust ports 19 are closed by the piston 13 and shortly thereafter the bottom of piston 16 covers the lower edges of ports 25. The air thus entrapped becomes compressed during the remainder of the inward stroke of the pistons and at a proper period of the cycle fuel is injected into the cylinder 17 through port 20 and is ignited by the heat of compression, in the usual manner.

When the yoke 15 moves downwardly from the position in which it is shown in Fig. 1, it causes air to be drawn from chamber 41 into chamber 22. If the check valve 34 is provided this action will start immediately. When the yoke has reached the lower limit of its stroke the chamber 22 will

be filled with air at approximately atmospheric pressure. The upward movement of the yoke 15 and piston 16 compresses the air in chamber 22 and inside of the piston until the piston ports 37 5 reach the cylinder ports 25. Further upward movement forces the air through ports 24 into the storage chambers 23 until the bottom of piston 16 uncovers the ports 25. Then the compressed air will pass from chambers 22 and 23 and piston 10 ton 16 through ports 37 and 25 into cylinder 17 with a swirling motion imparted by the oblique disposition of the ports, and from chambers 23 through ports 24 and 25 into the cylinder.

While it is desirable to prevent the compression 15 of air in the crank case, for the reason which has been set forth, a by-pass 21A in one of the walls of the head 21 from the crank case to the chamber 22 may be provided which is uncovered by the yoke 15 at the end of its suction stroke which 20 may admit air from the crank case to the compression chamber 22, but which will be closed by the yoke as it begins to rise to prevent the passage of air from the crank case into the compression chamber or into the engine cylinder.

25 With the arrangement herein disclosed, the inside of piston 16 together with the storage chambers 23 provide ample capacity for the compressed air to insure a complete and thorough scavenging operation. Moreover the separation of the crank 30 case from the parts of the engine from which the compressed air is delivered to the working cylinder effectively prevents the escape of lubricating oil from the crank case. The specific embodiment shown and described is for illustrative purposes only and I intend no limitations other than 35 those imposed by the appended claims.

What I claim is:

1. An internal combustion engine comprising 40 a working cylinder, an air compression chamber of greater cross sectional area than that of said cylinder, an inlet port thereto, a yoke forming a piston in said compression chamber, a hollow piston connected with the yoke and extending therefrom into said cylinder, elongated ports in the cylinder adapted to be uncovered by the end 45 of said hollow piston as it nears the end of its stroke, and ports in said hollow piston which register with said cylinder ports throughout the length thereof.

50 2. An internal combustion engine comprising a working cylinder, an air compression chamber of greater cross sectional area than that of said cylinder, an inlet port thereto, a yoke forming a piston in said compression chamber, a hollow piston 55 connected with the yoke and extending therefrom into said cylinder, elongated ports in the cylinder adapted to be uncovered by the end of said hollow piston as it nears the end of its stroke, an annular chamber surrounding said elongated ports, and ports in the said hollow piston which register with said cylinder ports throughout the length thereof.

60 3. An internal combustion engine comprising 65 a working cylinder, an air compression chamber of greater cross-sectional area than that of said cylinder, an inlet port thereto, a yoke forming a piston in said compression chamber, a hollow piston connected with the yoke and extending therefrom into said cylinder, elongated ports in the cylinder adapted to be uncovered by the end of said hollow piston as it nears the end of its stroke, an annular chamber surrounding said elongated ports, and a storage chamber communicating 70 therewith and ports in said hollow piston which 75

register with said cylinder ports throughout the length thereof.

4. An internal combustion engine comprising a working cylinder, an air compression chamber of greater cross-sectional area than that of said cylinder, an inlet port thereto, a yoke forming a piston in said compression chamber, a hollow piston extending therefrom into said cylinder, a self aligning connection between said hollow piston and the yoke, elongated ports in the cylinder 10 adapted to be uncovered by the end of said hollow piston as it nears the end of its stroke, and ports in said hollow piston which register with said cylinder ports throughout the length thereof.

5. An internal combustion engine comprising 15 a working cylinder, an air compression chamber of greater cross-sectional area than that of said cylinder, an inlet port thereto, a yoke forming a piston in said compression chamber, a hollow piston connected with the yoke and extending 20 therefrom into said cylinder, a check valve in said hollow piston, elongated ports in the cylinder adapted to be uncovered by the end of said hollow piston as it nears the end of its stroke, an annular chamber surrounding said elongated ports, and 25 ports in said hollow piston which register with said cylinder ports throughout the length thereof.

6. An internal combustion engine comprising a working cylinder, an air compression chamber of greater cross-sectional area than that of said cylinder, an inlet port thereto, a yoke forming a piston in said compression chamber, a hollow piston connected with the yoke and extending therefrom into said cylinder, elongated ports in the cylinder adapted to be uncovered by the end 35 of said hollow piston as it nears the end of its stroke, ports in said hollow piston which register with said cylinder ports throughout the length thereof, a second piston in the working cylinder, a crank shaft, a connection between the crank 40 shaft and said yoke and a connection between the crank shaft and said second piston.

7. An internal combustion engine comprising a working cylinder, a rectangular air compression 45 chamber of greater cross-sectional area than that of said cylinder, an inlet port thereto, a yoke forming a piston in said compression chamber, a hollow piston connected with the yoke and extending therefrom into said cylinder, elongated ports in the cylinder adapted to be uncovered by 50 the end of said hollow piston as it nears the end of its stroke, an annular chamber surrounding said elongated ports, and ports in said hollow piston which register with said cylinder ports throughout the length thereof.

8. An internal combustion engine comprising a working cylinder, an oblong rectangular compression chamber of greater cross-sectional area than that of said cylinder, an inlet port thereto, a yoke forming a piston in said compression 60 chamber, a hollow piston connected with the yoke and extending therefrom into said cylinder, elongated ports in the cylinder adapted to be uncovered by the end of said hollow piston as it nears the end of its stroke, an annular chamber 65 surrounding said elongated ports, and ports in said hollow piston which register with cylinder ports throughout the length thereof.

9. An internal combustion engine comprising a working cylinder, an oblong rectangular air 70 compression chamber of greater cross-sectional area than that of said cylinder, an inlet port thereto, a yoke forming a piston in said compression chamber, the ends of said yoke which abut against the shorter walls of the compression 75

- chamber being curved, a hollow piston connected with the yoke and extending therefrom into said cylinder, elongated ports in the cylinder adapted to be uncovered by the end of the said hollow piston as it nears the end of its stroke, an annular chamber surrounding said elongated ports, and ports in said hollow piston which register with said cylinder ports throughout the length thereof.
10. An internal combustion engine comprising a working cylinder, an oblong rectangular air compression chamber of greater cross-sectional area than that of said cylinder, an inlet port thereto, a yoke forming a piston in said compression chamber, a hollow piston extending therefrom into the cylinder, a self alining connection between the hollow piston and the yoke, elongated ports in the cylinder adapted to be uncovered by the end of said hollow piston as it nears the end of its stroke, an annular chamber surrounding said elongated ports, and ports in said hollow piston which register with said cylinder ports throughout the length thereof.
11. An internal combustion engine comprising a working cylinder, an oblong rectangular air compression chamber of greater cross-sectional area than that of said cylinder, an inlet port thereto, a yoke forming a piston in said compression chamber, a hollow piston connected with the yoke and extending therefrom into said cylinder, elongated ports in the cylinder adapted to be uncovered by the end of said hollow piston as it nears the end of the stroke, an annular chamber surrounding said elongated ports, storage chambers at the longer sides of the compression chamber communicating with said annular chamber, ports in said hollow piston which register with said cylinder ports throughout the length thereof, a crank case, a crank shaft therein, connecting rods between the crank shaft and the yoke and a by-pass between the crank case and the compression chamber arranged to be opened by the yoke at the end of its stroke.
12. An internal combustion engine comprising a working cylinder, an oblong rectangular air compression chamber of greater cross-sectional area than that of said cylinder, an inlet port thereto, a yoke forming a piston in said compression chamber, a hollow piston connected with the yoke and extending therefrom into said cylinder, elongated ports in the cylinder adapted to be uncovered by the end of said hollow piston as it nears the end of its stroke, an annular chamber surrounding said elongated ports, ports in said hollow piston which register with said cylinder ports throughout the length thereof, a crank shaft, and a connecting rod between the crank shaft and the yoke.
13. An internal combustion engine comprising a working cylinder, an oblong rectangular air compression chamber of greater cross-sectional area than that of said cylinder, an inlet port thereto, a yoke forming a piston in said compression chamber, the ends of said yoke which abut against the shorter walls of the compression chamber being curved, a hollow piston connected with the yoke and extending therefrom into said cylinder, elongated ports in the cylinder adapted to be uncovered by the end of said hollow piston as it nears the end of its stroke, an annular chamber surrounding said elongated ports, ports in said hollow piston which register with said cylinder ports throughout the length thereof, a crank shaft and connecting rods between the crank shaft and the yoke.
14. An internal combustion engine comprising a working cylinder, an oblong rectangular air compression chamber of greater cross-sectional area than that of said cylinder, an inlet port
- thereto, a yoke forming a piston in said compression chamber, the ends of said yoke which abut against the shorter walls of the compression chamber being curved, a hollow piston extending from the yoke into the cylinder, a self alining connection between the hollow piston and the yoke, a check valve in the hollow piston, elongated ports in the cylinder adapted to be uncovered by the end of said hollow piston as it nears the end of its stroke, an annular chamber surrounding said elongated ports, ports in said hollow piston which register with said cylinder ports throughout the length thereof, a crank shaft and connecting rods between the crank shaft and the yoke.
15. An internal combustion engine comprising a working cylinder, an oblong rectangular air compression chamber of greater cross-sectional area than that of said cylinder, an inlet port thereto, a yoke forming a piston in said compression chamber, the ends of said yoke which abut against the shorter walls of the compression chamber being curved, a hollow piston extending from the yoke into the cylinder, a self alining connection between the hollow piston and the yoke, a check valve in the hollow piston, elongated ports in the cylinder adapted to be uncovered by the end of said hollow piston as it nears the end of its stroke, an annular chamber surrounding said elongated ports, ports in said hollow piston which register with said cylinder ports throughout the length thereof, a crank shaft and connecting rods between the crank shaft and the yoke.
16. An internal combustion engine comprising a working cylinder, an oblong rectangular air compression chamber of greater cross-sectional area than that of said cylinder, an inlet port thereto, a yoke forming a piston in said compression chamber, a hollow piston connected with the yoke and extending therefrom into said cylinder, elongated ports in the cylinder adapted to be uncovered by the end of said hollow piston as it nears the end of its stroke, an annular chamber surrounding said elongated ports, ports in said hollow piston which register with said cylinder ports throughout the length thereof, a second piston in the working cylinder, a crank shaft, a connecting rod between the crank shaft and the second piston and connecting rods between the crank shaft and the yoke.
17. An internal combustion engine comprising a working cylinder, an oblong rectangular air compression chamber of greater cross-sectional area than that of said cylinder, an inlet port thereto, a yoke forming a piston in said compression chamber, the ends of said yoke which abut against the shorter walls of the compression chamber being curved, a hollow piston extending from the yoke into the cylinder, a self alining connection between the hollow piston and the yoke, a check valve in the hollow piston, elongated ports in the cylinder adapted to be uncovered by the end of said hollow piston as it nears the end of its stroke, an annular chamber surrounding said elongated ports, storage chambers at the longer sides of the compression chamber communicating with said annular chamber, ports in said hollow piston which register with said cylinder ports throughout the length thereof, a crank shaft and connecting rods between the crank shaft and the yoke.

second piston in the working cylinder, a crank case, a crank shaft therein, a connecting rod between the crank shaft and said second piston, connecting rods between the crank case and the 5 yoke and a by-pass between the crank case and the compression chamber arranged to be opened by the yoke at the end of its stroke.

18. An internal combustion engine comprising a working cylinder, an air compression chamber 10 of greater cross-sectional area than that of said cylinder, an inlet port thereto, a yoke forming a piston in said compression chamber, a hollow piston connected with the yoke and extending therefrom into said cylinder, elongated transversely oblique ports in the cylinder adapted to 15 be uncovered by the end of said hollow piston as it nears the end of its stroke, an annular chamber surrounding said elongated ports and transversely oblique ports in the said hollow piston 20 ton which register with said cylinder ports throughout the length thereof.

19. An internal combustion engine comprising a working cylinder, an oblong rectangular air compression chamber of greater cross-sectional 25 area than that of said cylinder, an inlet port thereto, a yoke forming a piston in said compression chamber, the ends of said yoke which abut against the shorter walls of the compression chamber being curved, a hollow piston extending 30 from the yoke into the cylinder, a self aligning connection between the hollow piston and the yoke, a check valve in the hollow piston, elongated transversely oblique ports in the cylinder adapted to be uncovered by the end of said hollow 35 piston as it nears the end of its stroke, an annular chamber surrounding said elongated ports, storage chambers at the longer sides of the compression chamber communicating with said annular chamber, transversely oblique ports in said 40 hollow piston which register with said cylinder ports throughout the length thereof, a second piston in the working cylinder, a crank case, a crank shaft therein, a connecting rod between the crank shaft and said second piston, connecting 45 rods between the crank shaft and the yoke and a by-pass between the crank shaft and the compression chamber arranged to be opened by the yoke at the end of its stroke.

20. An internal combustion engine comprising 50 a working cylinder, an oblong rectangular air compression chamber of greater cross-sectional area than that of said cylinder, an inlet port thereto, a yoke forming a piston in said compression chamber, the ends of said yoke which abut against the shorter walls of the compression 55 chamber being curved, a hollow piston extending from the yoke into the cylinder, a self aligning connection between the hollow piston and the yoke, elongated ports in the cylinder adapted to 60 be uncovered by the end of said hollow piston as it nears the end of its stroke, an annular chamber surrounding said elongated ports, storage chambers at the longer sides of the compression chamber communicating with said annular chamber, ports in said hollow piston which register with 65 said cylinder ports throughout the length thereof, a second piston in the working cylinder, a crank case, a crank shaft therein, a connecting rod between the crank shaft and said second piston, and connecting rods between the crank 70 case and the yoke.

21. An internal combustion engine comprising 75 a working cylinder, an oblong rectangular air compression chamber of greater cross-sectional area than that of said cylinder, an inlet port

thereto, a yoke forming a piston in said compression chamber, the ends of said yoke which abut against the shorter walls of the compression chamber being curved, a hollow piston extending from the yoke into the cylinder, a self aligning connection between the hollow piston and the yoke, elongated transversely oblique ports in the cylinder adapted to be uncovered by the end of said hollow piston as it nears the end of its stroke, an annular chamber surrounding said 10 elongated ports, storage chambers at the longer sides of the compression chamber communicating with said annular chamber, transversely oblique ports in said hollow piston which register with said cylinder ports throughout the length 15 thereof, a second piston in the working cylinder, a crank case, a crank shaft therein, a connecting rod between the crank shaft and said second piston, and connecting rods between the crank shaft and the yoke. 20

22. In internal combustion engine construction, in combination, a compression chamber, a storage compartment communicable with said chamber, a cylinder, a pair of oppositely disposed pistons in said cylinder, and a yoke associated 25 with one of said pistons and slidably fitted in said compression chamber to create pressure in said chamber and said compartment.

23. In internal combustion engine construction, in combination, a compression chamber, a 30 storage chamber communicable with said compression chamber, a cylinder, a pair of oppositely disposed pistons in said cylinder, and a yoke associated with one of said pistons and slidably fitted in said compression chamber to create 35 pressure in said compression chamber, said storage chamber being connected to said cylinder during a portion of the stroke of said last-mentioned piston.

24. In internal combustion engine construction, in combination, a compression chamber, a storage chamber communicable with said compression chamber, a cylinder, a piston in said cylinder, a crank shaft, means connecting said crank shaft to said piston, and means for self-aligning said last-mentioned means. 40

25. In internal combustion engine construction, in combination, a compression chamber, a storage chamber, a cylinder, a piston disposed within said cylinder and having ports therein 50 whereby air compressed in said compression chamber flows into said storage chamber, a crank shaft, means connecting said crank shaft to said piston, a second piston mounted in said cylinder, and means connecting said last-mentioned piston 55 to said crank shaft, said last-mentioned means being associated with said compression chamber and being self-aligning.

26. In internal combustion engine construction, in combination, a cylinder, a hollow piston disposed within said cylinder, a compression chamber, means connected to said piston and adapted to reciprocate in said compression chamber to create pressure, and means forming an enclosure, the interior of said piston being in 65 communication with said chamber, and said piston and said enclosure having ports therein adapted to register during a portion of the stroke of said piston. 60

27. In internal combustion engine construction, in combination, a cylinder, a compression chamber, a part including a piston in said cylinder adapted to reciprocate in said compression chamber and said cylinder, means forming an enclosure, and means in said piston forming a 70 75

- communication between said chamber and said enclosure, said enclosure having ports in communication with said cylinder, said part adapted to reach a position in its stroke which uncovers 5 said ports so that said enclosure is in communication with said cylinder.
28. In internal combustion engine construction, in combination, a crank case, a cylinder, a pair of opposed pistons, means in said crank case 10 for driving said pistons, said cylinder having exhaust ports formed in its wall opened and closed by one of said pistons, a compression chamber including means adapted to prevent air compression in said crank case, and means associated 15 with the other of said pistons for creating a pressure in said compression chamber, said cylinder having ports formed in its wall in communication with said compression chamber and adapted to be opened and closed by said last-mentioned piston, said first-mentioned piston adapted to close said first-mentioned ports before 20 said second-mentioned piston closes said second-mentioned ports.
29. In internal combustion engine construction, in combination, a cylinder having exhaust ports formed in its wall, a piston adapted to reciprocate in said cylinder to open and close said exhaust ports, a compression chamber, a hollow piston member adapted to reciprocate in said 25 cylinder, a part connected to said hollow piston member and adapted to reciprocate in said compression chamber to compress air therein, and a secondary chamber adjacent said cylinder, said cylinder having ports formed therein in communication with said secondary chamber, said hollow piston member having ports in communication with said compression chamber and adapted to register with said last-mentioned ports during a portion of the stroke of said piston member whereby said compression chamber is in communication with said secondary chamber during a portion of the stroke of said hollow piston member, said hollow piston member adapted to open said second-mentioned ports during 40 a portion of its stroke and said piston adapted to close said exhaust ports while said second-mentioned ports still remain open.
30. In internal combustion engine construction, in combination, an air compression chamber, a storage chamber communicable with said compression chamber, a cylinder communicable with said storage chamber, a hollow piston having ports therein, said piston being adapted to reciprocate within said cylinder, and means associated 45 with said piston and adapted to force air into said storage chamber through said piston and said ports.
31. In internal combustion engine construction, in combination, a compression chamber, a cylinder, a pair of oppositely disposed pistons in said cylinder, and means associated with one of said pistons adapted to create pressure in said chamber, said means having rounded portions slidably associated with the walls of said compression chamber and adapted to compensate angular displacement of said means to maintain an aligned relation between said means and the walls of said compression chamber.
32. In internal combustion engine construction, in combination, a compression chamber, means forming a chamber for storing compressed air compressed in said compression chamber, said means being communicable with said compression chamber, and means adapted to compress 50 air in said chamber, said means including a work- 55 ing piston forming openings to accommodate the flow of compressed air from said compression chamber into said first-mentioned means.
33. In internal combustion engine construction, in combination, a cylinder, a piston disposed within said cylinder, a crank shaft, a compression chamber disposed about said cylinder, a yoke secured to the top of said piston and adapted to reciprocate in said chamber, and means connecting said yoke to said crank shaft, said yoke comprising a compressing piston and including portions adapted to compensate angular displacement of said yoke to maintain said yoke in self-aligning relation with said chamber.
34. In internal combustion engine construction, in combination, a compression chamber, a storage chamber communicable with said compression chamber, a cylinder communicable with said chambers, a hollow working piston reciprocable in said cylinder and having ports formed therein and a compression piston associated with said working piston and adapted to reciprocate in said compression chamber, said chambers being in communication by way of said hollow piston and said piston ports when said piston is near the top of its stroke and before communication is established between said chambers and said cylinder.
35. In internal combustion engine construction, in combination, a compression chamber, a storage chamber communicable with said compression chamber, a cylinder, a hollow working piston reciprocable in said cylinder and having ports formed therein adapted to connect said chambers during a portion of the stroke of said piston, a compression piston associated with said working piston for compressing air in said compression chamber, and means for putting said compression chamber into communication with the interior of said hollow piston during a portion 40 of its stroke whereby air compressed in said compression chamber flows through said piston into said storage chamber.
36. In internal combustion engine construction, in combination, a compression chamber, a storage chamber communicable with said compression chamber, a cylinder communicable with both of said chambers, a hollow working piston in said cylinder and ports formed in said piston adapted to connect said chambers during a portion of the stroke of said piston, and said ports in said piston being openable during the up stroke of said piston to connect said chambers.
37. In internal combustion engine construction, in combination, a compression chamber, a storage chamber communicable with said compression chamber, a cylinder, means forming a hollow piston having ports and a one-way valve, said piston being reciprocable in said cylinder, and means to connect said chambers during a portion of its stroke.
38. In internal combustion engine construction, in combination, a compression chamber, a storage chamber communicable with said compression chamber, a cylinder communicable with said chambers, a hollow working piston reciprocable in said cylinder and having ports formed therein to connect said chambers during a portion of the stroke of said piston, a compressing member secured to said piston for reciprocation in said compression chamber, and one-way valve means associated with said hollow piston to connect said compression chamber and the interior of said hollow piston during a portion of the stroke thereof.

39. In internal combustion engine construction, in combination, a compression chamber, a storage chamber communicable with said compression chamber, a cylinder, a pair of oppositely disposed pistons in said cylinder, one of said pistons being hollow and having ports formed therein to connect said chambers during a portion of the stroke of said hollow piston, and valve means in said hollow piston adapted to connect said compression chamber and the interior of said hollow piston during a portion of its upward stroke.

40. In internal combustion engine construction, in combination, a compression chamber, a storage chamber, a cylinder, a pair of oppositely disposed pistons in said cylinder, one of said pistons being hollow and having ports formed therein to connect said chambers and said cylinder during a portion of the stroke of said

hollow piston, valve means in said hollow piston openable during the up stroke thereof to connect said compression chamber with the interior of said hollow piston, and means connected to said hollow piston for compressing air in said compression chamber.

41. In internal combustion engine construction, in combination, a compression chamber, a cylinder, a pair of oppositely disposed pistons in said cylinder, one of said pistons being hollow, means forming a port in said cylinder to connect said chamber and said cylinder by way of said hollow piston and said ports during a portion of the stroke of said hollow piston, and valve means connected to said hollow piston and openable during the up stroke thereof whereby air compressed in said compression chamber is admitted into said hollow piston.

WILHELM B. BRONANDER.
